UNITED STATES PATENT OFFICE.

FRANK L. CHIPMAN, OF EASTON, PENNSYLVANIA, ASSIGNOR TO CHIPMAN KNITTING MILLS, OF EASTON, PENNSYLVANIA, A CORPORATION OF PENNSYLVANIA.

HOSIERY.

Application filed January 25, 1924. Serial No. 688,441.

My improvements relate to the employment of metallic thread in connection with the knitting of certain selected courses of stockings, preferably in the region of welt 5 of long hose, or the top of short hose, said courses being knit with metallic threads that increases the constrictive or gripping qualities of such courses relative to the fabric body knit, helping to sustain the stocking in place, acting as anti-ravel bands, and appearing by contrast of the luster of the metal, as ornamental and characterizing horizontal stripes about the stockings.

In the drawings, Fig. I represents in outline long hose conveniently embodying my invention.

Fig. II is an enlarged view of that portion of the stocking fabric within the rectangle II-II in Fig. I.

Fig. III is an enlarged sectional view along the line III-III in Fig. I.

Fig. IV is an outline view of half-hose knit in accordance with my invention; and

Fig. V is an enlarged view of that portion 25 of the stocking fabric within the rectangle V-V in Fig. IV.

It is characteristic of this invention that certain selected courses of a stocking are knit with a fine metallic thread which is 30 sufficiently flexible to permit of its being worked by the needles of a knitting machine, yet adequately strong to set up the constrictive qualities desired as hereinafter explained.

Referring first to Figs. I, II and III of the drawings, it will be observed that the long hose as therein shown has a deep welt 2, and immediately below said welt, a horizontal circumferential stripe 3 containing metallic thread. This stripe 3 is formed in the present instance by knitting a metallic thread 4 conjointly with the ordinary or body yarn 5 from which the rest of the stocking is knit, for several successive 40 courses, for example three such courses being illustrated diagrammatically in Fig. II. The result of the course or courses thus knit with metallic thread 4 is to give to the upper part of the stocking a greater constrictive or gripping capacity than possible of attainment in a stocking knit wholly from cotton or silk yarn, since the knitting of the metal thread tends to retract the stripe or band 3 to its original position after it has

been expanded in use. Or, in other words, 55 the stripe 3 embodying knit metallic thread 4 is resistive of expansion to a relatively greater degree than the body fabric of silk or other yarn and thus performs to some extent the function of a garter to hold the 60 stocking in place on the leg of the wearer, such tendency remaining permanent notwithstanding subsequent laundering of the stocking. Another function of a course or 65 courses knit with metallic thread 4 is to check raveling, the fabric loops knit with such metallic thread 4 possessing sufficient set to resist downward ravel along any given wale wherein one of the loops above the course or courses has broken. For example, 70 if in the stocking shown in Fig. I, such a break occurs anywhere in the welt 2, (and this is where rupture is usually occasioned by pinching during attachment of a garter), the downward ravel which is thereupon 75 liable to ensue, is checked at the course or courses containing the metallic thread 4 and proceeds no further.

Although the metallic thread 4 may be incorporated in the fabric after the manner 80 of splicing yarn, I preferably so feed it to the needles as to overlie the body yarn at the face side of the fabric. Such a relation of the threads may be had by a well known method ordinarily termed "plaiting." The 85 stripe produced in this way is therefore ornamental as well as useful in the manner above explained.

In Fig. IV, I have illustrated an infant's hose having a ribbed top 10 with three separate horizontal stripes 11, each of which is knit in accordance with my invention with metallic thread 4 as shown in Fig. V. In this instance the metallic thread 4 is knit for three successive courses by itself, i. e., 90 without employing any of the body yarn 5 from which the remainder of the stocking is knit. Here, as in the first described embodiment, the constrictive power of the knitted metallic thread gives the top 10 of the stocking permanent power of grippage 95 around the calf of the leg after the manner of a garter to hold the stocking in place, at the same time serving the further useful function of preventing raveling.

It is of course to be understood that I do not wish to be limited to the precise allocation of the metallic courses on the stockings

as herein specifically described, since the positioning may obviously be varied in accordance with the character or style of the hosiery without departing from the spirit of my invention.

Having thus described my invention, I claim:

1. A stocking knit of textile material having one or more courses of metallic thread 10 to form an anti-ravel constrictive stripe.
2. A stocking knit of textile material having one or more horizontal courses of metallic thread thereby providing an anti-ravel constrictive stripe or stripes.
- 15 3. A stocking knit of textile material having one or more courses of metallic thread

in the region of the welt to provide an anti-ravel constrictive stripe or stripes.

4. A stocking knit of textile material having one or more courses wholly of metallic 20 thread to form anti-ravel constrictive portions functional as a garter.

5. A stocking knit of textile material having one or more courses of metallic thread 25 plated relative to the body yarn to form an anti-ravel constrictive stripe functional also as a garter.

In testimony whereof, I have hereunto signed my name at Easton, Pennsylvania, this 19th day of January, 1924.

FRANK L. CHIPMAN.
